UNITED STATES PATENT OFFICE.

HENRY F. BELCHER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,973, dated December 7, 1897.

Application filed November 1, 1897. Serial No. 657,107. Term of patent 14 years.

To all whom it may concern:

Be it known that I, HENRY F. BELCHER, a citizen of the United States, residing at Chicago, in the county of Cook and State of Illinois, have invented a certain new and original Design for Prism-Lights, of which the following is a specification.

My invention relates to designs for prism-lights.

Figure 1 is a plan view of a prism-light embodying my design. Fig. 2 is a cross-section therethrough.

A is the body of the prism-light; B, a design thereon placed upon the inclined surfaces C C of the prisms D D and arranged so as to give the appearance of a complete design.

When a prism-light of my design is examined, there is a continually-changing effect of the design due to the presence of the prisms

as a field and due to the changing in position of the person who is observing the light. There is a great variation, particularly with reference to such lines in the design as lie diagonally across the prisms.

The essential features of my design are found in a prism-light comprising a substantially flat relatively thin body having a series of prisms on one side and a design produced upon the inclined surfaces of such prism and forming lines which appear to lie across the prisms.

I claim—

A design for a prism-light, substantially as shown and described.

HENRY F. BELCHER.
